UNITED STATES PATENT OFFICE.

WILLIAM BAXTER, JR., OF BALTIMORE COUNTY, MARYLAND.

OVERLOADING AND SLACK CABLE-STOP FOR ELECTRICAL HOISTING-MACHINES.

SPECIFICATION forming part of Letters Patent No. 394,952, dated December 25, 1888.

Application filed February 28, 1888. Serial No. 265,575. (No model.)

To all whom it may concern:

Be it known that I, WILLIAM BAXTER, Jr., a citizen of the United States, residing in the county of Baltimore, State of Maryland, 5 have invented certain new and useful Improvements in Overloading and Slack Cable- Stops for Electrical Hoisting-Machines, fully described and represented in the following specification and the accompanying drawings, forming a part of the same.

This invention relates to that class of hoisting-machines in which an electric motor is used for actuating the hoisting mechanism, and the hoisting car or platform is elevated 15 (by such mechanism) in a vertical or inclined hoistway; and the object of this invention is to provide any such hoisting mechanism with means for stopping the electric motor automatically when, on the one hand, the car is overloaded, or, on the other hand, when the car or its counter-balance is obstructed, so 20 that the hoisting-rope becomes slack or overstrained.

It is well known that in electric motors operated at a constant potential the current 25 passing through the motor increases with the resistance opposed to its rotations, and the overloading of the hoisting mechanism, which would impose upon the motor a resistance 30 greater than its normal capacity, would therefore tend to increase the current to such an extent as to burn out the armature and to thus ruin the machine.

My present invention provides an electric 35 switch which is operated automatically by the movement of some support which sustains the weight or pressure of the car, and which is adapted to yield when the car is either overloaded or obstructed.

40 My invention also includes an automatic indicator, as a bell, operated by a yielding connection with the car when overloaded, to warn the conductor that a portion of the load must be removed, an electric circuit being 45 derived from the main motor-circuit or from a local battery carried upon the moving car or platform to actuate the indicator, if a magnetic device be used. The yielding support, affected by the variable load in the car, must 50 of necessity be located between the hoisting device and the car-platform, and may therefore be combined with a pulley-bearing, over

which the hoisting-rope is conducted, with an elastic connection between the car and its suspending-rope, or with any other element 55 of the hoisting device which is affected by the load imposed. If the hoisting mechanism continues to pay out the suspending-rope when the car is obstructed in its downward motion, such rope is liable to be greatly de- 60 ranged when again wound up, or is liable to rupture if the obstruction to the car be suddenly removed and the car allowed by the slack in the rope to fall a considerable distance. When a counter-balance is used and 65 connected with the car by a rope, the evils arising from an obstruction of the counter- balance are nearly as great as those affecting the car, and my appliances are equally applicable for automatically stopping the elec- 70 tric motor when the counter-balance is obstructed in its movement, so as to slacken or tighten its suspending-rope.

My improvements will be understood by reference to the annexed drawings, in which— 75

Figure 1 is a diagram of an electric motor actuating a hoisting apparatus, the drum of which is connected by a rope with a suspended car, and the motor-circuit conveyed to the car by a cable to actuate an electric indicator therein. The circuit in this figure is arranged to operate with constant potential an independent battery with a local circuit, also indicated in dotted lines within the car. Fig. 2 is a diagram showing a yielding bearing for the counterbalance-pulley, a motor-circuit adapted to operate with constant current, and an electric switch actuated by the movement of the yielding bearing to short-circuit such motor when the car is overloaded. 80 Figs. 3, 4, and 5 show constructions for the yielding-car connection. Fig. 6 is a diagram of the constant potential switch with circuit 85 opened.

In Fig. 1, H is a hoisting-machine actuated 95 by electric motor M. P are the posts of the hoistway; P', a beam across the top, supporting a counterbalance-pulley, I, and two guide-pulleys, J and K, leading the hoisting-rope L from the hoister-drum to the car C. A counter-balance, C', is connected with the car by a rope, C'', passed over the pulley I. A pulley, N, is arranged below the level of the hoisting-drum to guide the rope L downward 100

from the latter to illustrate the application of a yielding bearing to sustain an upward pull. The motor is connected with an electric circuit by wires w w' , the current being connected with switches s , s' , and s^2 , which are actuated, respectively, by the bearings of the pulleys K, N, and I. The conductors w w' are also connected through a flexible cable, Q, to a switch, s^3 , inside the car, which is activated when the car is overloaded to operate a suitable indicator and notify the attendant that it would be injurious to start the motor. Such switch is moved by a yielding connection between the car and its suspending-rope, and is thus affected by the load placed upon the car-platform. The yielding connection consists in a sliding bolt, D, fitted through the roof of the car, with a head, d, upon its inner end and a spring, b, inserted between the head and the car-beam b'. The rope being attached to the outer end of the bolt, it is evident that the load placed upon the car-platform p would operate to compress the spring and move the head d toward the top of the car. A bell, g, is shown fixed within the car, with a magnet, G, to actuate its hammer g' electrically.

e e' are the terminals of the circuit-wires, conducted to the car through the cable Q, and are formed as springs, one of which is arranged in the path of the bolt-head d, to be moved when the spring b is abnormally compressed.

The springs e e' are mounted upon a switch-base, s^3 , to adjust the spring e in such relation to the bolt-head d that when the proper load upon the platform of the car is exceeded it will be pressed against the spring e' and the circuit closed through the bell-magnet G to operate the alarm as desired.

The use of a bell serves to call the operator's attention more forcibly than an index-hand upon a dial; but it is obvious that any form of annunciator may be operated by the circuit, when closed, through the springs e e' . It is also obvious that a local battery carried within the car may be used instead of a branch of the motor-circuit, and such battery is indicated at q, with dotted connections w^2 and w^3 , leading, respectively, to the magnet G and the spring e, like the terminals of the wires w w' .

Three different forms of yielding bearing are shown in connection with the pulleys I, K, and N, that for the pulley I consisting in a pedestal, B, having one end of its foot resting upon a spring, t, adapted to yield when the normal pressure upon the pulley-shaft B' is varied. The other end of the pedestal-foot is connected with its supporting-beam P' by a hinge, B², and the movable end of the foot is connected by a pin, c, with a switch-lever, c'. The switch-lever is actuated by the movement of the foot to open the circuit and stop the motor when the counter-balance is obstructed in its movement, so as to sufficiently vary the pressure upon the bearing B.

The movable end of the switch operates

normally to unite two contacts, d', to maintain a closed circuit, as shown in Fig. 1, and the weight of the car and counter-balance operate 70 normally to compress the spring t to the point at which the switch is adjusted to close the circuit. The switch is therefore adapted to open the circuit and stop the motor if moved in either direction, and an obstruction to the 75 counter-balance in its downward movement, which would tend to slacken the pressure upon the bearing B, thus permits the spring t to raise the movable end of its foot and move the switch with the same effect as when 80 the pressure upon the bearing was increased. As the ropes pass over the pulley K in a horizontal and vertical direction, the resultant pressure is at an angle with both ropes, and the box f, supporting the pulley-axle K', is 85 shown guided in an inclined socket provided with a pin to actuate a switch-lever, c', as just described. To sustain the box against the pressure of the rope, a bent lever, f', is pivoted upon the pulley-stand and coupled with 90 the box by link l'. The lever is provided with sliding weight f², which is adjusted to balance the proper load, so as to hold the switch in its neutral position to close the circuit between the contacts d'. The metallic 95 connection c² between the blocks d' is lapped upon each far enough to permit a normal movement of the bearing f and B within the limits of an ordinary load without breaking the connection between the blocks and stopping the motor; but an obstruction to the car in its downward movement would diminish the pressure upon the bearing and break the circuit by moving the switch in one direction, while an overload upon the car would cause 105 the breaking of the circuit by moving the switch in the opposite direction, as described for the bearing B.

The bearing for the pulley N is formed at the end of a hinged arm, N', with a spring, n², 110 above the bearing to allow of its yielding like those last described.

The switch c' is connected with the bearing by a pin, as in the other constructions, and the circuit through the motor is connected 115 in series with its contact-blocks d', so that the circuit may be broken by a suitable movement of the switch.

In Fig. 2 is shown the construction for the switches to operate with constant current, and 120 a cut-out switch is shown within the car to be actuated by the bolt-head d with either a slack-cable or overload for cutting out the motor and stopping the hoisting mechanism 125 automatically. The switch is the same as that shown at the upper part of the figure, actuated by the yielding pulley - bearing over which the suspending-rope is carried, and the motor for operating the hoisting mechanism is merely indicated with its operative circuit, 130 as my improvement relates only to the electrical connections. The motor - circuit is shown in the wires a⁴ a⁵, connected with the positive and negative line-wires, and the two

- switches are adapted to make a connection in a loop of the said circuit, and to thereby short-circuit the motor and cause its immediate stoppage when either switch is operated.
- 5 The switch-lever in the car is shown actuated by a pin, d' , upon the bolt-head d , so that the movement of the bolt-head will actuate the switch-lever the same as the movement of the yielding-bearings heretofore described.
- 10 Each switch is provided with two contacts, a' , both connected with the same circuit-wires a^2 , and the other circuit-wire, a^3 , is connected with a metallic piece, a^6 , upon the switch-lever c' . The piece or block a^6 is normally separated from the contacts a' with a space between such parts sufficient to allow the movement of the lever c' within the normal variations of the load, while any variations above or below the normal would move 20 the block a^6 into contact with one of the pieces a' , and thus short-circuit the motor, as desired.
- 15 It is obvious that either of the switches illustrated would effect the desired object, and that both would not be required in the same construction, the drawings being furnished with both the switches merely to illustrate a variety of applications.
- 25 The circuit is conveyed to the car through 30 two conductors, d^2 and d^3 , shown, for convenience, fixed at opposite sides of the car in the hoistway, with brushes or contacts d^4 sliding over them with the movement of the car, and the circuit-wires a^2 and a^3 connecting such 35 brushes with the contacts a' in the car-switch.

It is obvious that the current could be conveyed to the car by a cable, as shown in Fig. 1, or by any other suitable means. The indicator or bell (shown in Fig. 1) would preferably be set to give its alarm with a somewhat lighter load than that required to operate any of the motor-switches shown applied to the yielding bearings, so as to give warning to the operator in time to avoid the actuation of such switches.

If an automatic motor-switch were not provided, any obstruction to the movement of the car or counter-balance when ascending would 40 not operate directly to stop the motor, but it would continue its revolution until its force were balanced by the strain on the ropes, and this strain might be sufficient to do serious 45 damage to the mechanism.

50 Where iron or steel ropes are used their entanglement or winding over one another upon the drum causes short bends and inflicts serious injury upon them; but such injuries may be wholly avoided by a suitable adjustment of the devices shown herein to effect the stoppage of the motor before the ropes become slack enough to leave the grooves in the drum.

55 It is obviously immaterial what means are employed to balance the tension upon the yielding bearing or suspending-rope, provided the pressure or weight of the car be sustained

at some point between the hoisting device and car-platform by a yielding support adapted to move an electric switch in the manner set forth.

60 The operation of the switches with constant current and constant potential circuits is substantially opposite, as is common with such circuits, the motor being stopped in the one ease by short-circuiting and in the other by opening the circuit; but the automatic switches may be made of any construction adapted to control the movements of the electric motor and hoisting mechanism, as desired.

65 It is obviously immaterial how the power of the motor be applied to move the load, as the connection between the motor and the car-platform would in any case afford an opportunity for the insertion of a yielding support to actuate a switch, as required in my invention.

70 It will be noticed, although several different constructions for the automatic switch are shown in Fig. 1, that in practice a single switch at any convenient point in the circuit is all that would be required, and the arrangement of the several switches in series in the diagram is shown only to illustrate their 75 mode of operation and would not be required in practice. It will be also understood that the particular construction for the yielding bearing is immaterial, and that a weight, a spring, or any other suitable resistance may 80 be opposed to the load upon the rope to hold the bearing and switch normally in a position to operate, as desired. It is also immaterial how the yielding connection to the car be constructed, and I have shown in Figs. 3, 4, and 85 90 95 100 105 110 115 120 125 130 a variety of such constructions to illustrate the scope of my invention. Each of these yielding connections is shown operating a switch connected with the terminals of an electric circuit, and such circuit may be employed either to stop the motor or to operate a bell or indicator, as may be desired.

In Fig. 3 the rope L is attached to the short arm of a lever, L' , pivoted upon the top of the car, and a weight is connected with the long arm of the lever to counterbalance the pull on the rope to a certain limit. The end of the lever is linked to a multiplying-lever, c' , connected with a pneumatic bell-push, c^5 , the bell c^6 being shown just below it, and the excessive load upon the car would operate to move the lever and actuate the bell-push and bell, as desired.

In Fig. 4 the rope L is shown passed between two guide-pulleys, l' , which are pivoted upon a frame, m^1 , adapted to turn upon the top of the car and to strain the suspending-rope out of its normal vertical position. The tension upon the pulleys is produced by a spring, m^3 , attached to the top of the car and to the frame m^4 , and operates normally to bend the rope in a certain degree until the load upon the car becomes excessive. The frame is linked to a switch, c' , and such excessive load

is shown operating, by straining the rope L, to tip the frame against the tension of the spring and to shift the switch as desired.

In Fig. 5 the rope L is connected with the top of the car through the medium of a couple of toggles, which are attached at their ends to the car and to the rope, a spring, n⁴, being inserted between them to press their middle joints apart. Any excessive tension upon the rope operates to compress the spring and to move an arm, n⁵, connected with one of the toggles and to a switch, c', suitable for a constant potential circuit.

In any of these constructions a weight or spring may be used at pleasure, or any other suitable means may be employed to perform the same function.

Any of the yielding bearings or connections shown herein may obviously be employed to actuate the indicator or bell by other mechanical means than a pneumatic bell independently of an electro-magnet.

Having thus set forth my invention, what I claim herein is—

- 25 1. In an electrical elevator system, the combination, with an electric motor, a hoisting device operated thereby, and a moving car suspended by a rope from a hoisting device, of a yielding support sustaining the pressure of the rope between the hoisting device and the car-platform and an electric switch in the motor-circuit actuated by the movement of such yielding support to stop the electric motor.
- 35 2. In an electrical elevator system, the combination, with an electric motor, a hoisting device operated thereby, and a moving car suspended by a rope from the hoisting device, of a pulley sustaining the pressure of the rope, a movable or yielding bearing for supporting the pulley-axle, and an electric switch actuated by the movement of the bearing to stop the electric motor, as and for the purpose set forth.
- 45 3. In an electrical elevator system, the combination, with an electric motor, a hoisting device operated thereby, and a moving car suspended by a rope from the hoisting device, of a pulley sustaining the pressure of the rope, a movable or yielding bearing for supporting the pulley-axle, a spring or weight adjusted to sustain the bearing under a given load, and an electric switch actuated by the movement of the bearing to stop the electric motor when such load is exceeded.
- 55 4. In an electrical elevator system, the combination, with an electric motor, a hoisting device operated thereby, and a moving car suspended by a rope from the hoisting device, of a pulley sustaining the pressure of the rope, a movable or yielding bearing for supporting the pulley-axle, and an electric switch actuated by the movement of the bearing to close

a short circuit around the motor, as and for the purpose set forth.

5. In an electrical elevator system, the combination, with an electric motor, a hoisting device operated thereby, and a moving car suspended by a rope from the hoisting device, of a pulley sustaining the pressure of the rope, a movable or yielding bearing for supporting the pulley-axle, a counter-balance connected with the car by a suitable rope, a pulley with yielding bearing for sustaining said rope, and electric switches applied to both of said yielding bearings for stopping the motor, substantially as herein set forth.

6. In an electrical elevator system, the combination, with a suspended car, of a yielding connection between the car and its suspending-rope, an electric circuit connecting the car with the electric motor, and a switch in such circuit upon the car, actuated by said yielding connection to stop the motor when the car is obstructed in its movement.

7. The combination, with a hoisting device and a moving car suspended by a rope therefrom, of a yielding support sustaining the pressure of the rope between the hoisting device and the car-platform, and a bell or indicator actuated by the movement of such yielding support, as and for the purpose set forth.

8. In an electrical elevator system, the combination, with a suspended car, of a yielding connection between the car and its suspending-rope, a magnetic bell or indicator, an electric circuit for operating the same, and a switch arranged in said circuit and actuated by the yielding rope-connection to operate the bell or indicator.

9. In an electrical elevator system, the combination, with a suspended car, of a rope connected with the car by an adjustable spring-coupling, a magnetic bell or indicator upon the car and an electric circuit for operating the same, and a switch arranged in said circuit and actuated by the spring-coupling, when the maximum load is imposed upon the car, to operate the bell or indicator, substantially as herein set forth.

10. In an electrical elevator system, the combination, with a suspended car, of a yielding connection between the car and its suspending-rope, a magnetic bell or indicator, and an electric circuit for operating the same, a local battery carried by the car for operating such circuit, and a switch arranged in said circuit and actuated by the yielding rope-connection to operate the bell or indicator.

In testimony whereof I have hereunto set my hand in the presence of two subscribing witnesses.
